W. C. NEAHR.
ELECTRIC LOCK SWITCH.
APPLICATION FILED JUNE 4, 1913.

Patented Oct. 27, 1914.

UNITED STATES PATENT OFFICE.

WILL C. NEAHR, OF DENVER, COLORADO, ASSIGNOR TO THE PROTECTIVE SIGNAL MANUFACTURING COMPANY, A CORPORATION OF COLORADO.

ELECTRIC LOCK-SWITCH.

1,115,092.

Specification of Letters Patent.

Patented Oct. 27, 1914.

Application filed June 4, 1913. Serial No. 771,738.

To all whom it may concern:

Be it known that I, WILL C. NEAHR, a citizen of the United States, residing at Denver, in the county of Denver and State 5 of Colorado, have invented certain new and useful Improvements in Electric Lock-Switches, of which the following is a specification.

My invention relates to electric lock switches and its object resides in providing 10 in operative connection with a circuit controlling switch, a mechanism which can be actuated only by the use of a special key, and which, after it has operated the switch 15 to reverse the condition of an electric circuit in which the latter is connected, will be automatically locked in its adjusted position and at the same time prevent the removal of the key until the mechanism is 20 released by the separate adjustment of its locking means.

By securing the key against removal from the instrument after the switch has been operated by the use thereof to either close 25 a normally open circuit or open a normally closed circuit, I attain the following results: 1st, the presence of the key on the instrument indicates that it was by operation of the latter that the condition of the circuit 30 was reversed, 2nd, a person after having operated the switch cannot restore the circuit to its original condition without having the means and knowledge for releasing the mechanism by adjustment of its locking 35 means, and only duly authorized persons can return the operative parts of the switch to their normal position, and 3rd, by providing the keys used to operate the switch, with numbers or other distinguishing marks, 40 the connection of the key with the instrument not only establishes the fact that the latter has been operated to reverse the condition of the circuit in which it is connected, but also indicates what particular person 45 performed the operation.

While my invention may be advantageously employed for many different purposes, it is particularly adapted for use in connection with an electric signaling or annunciating system such as those used to audibly or visually announce the approach of an engine or train at road crossings, stations

and other points of a railway line. When in a system of this type, a visible signal such as a semaphore remains in its danger indicating position after a train has passed the point of its location, or if a gong or other audible signal is sounded longer than a predetermined period, the circuit in which the instrument or instruments are located is deranged either by short-circuiting in case a normally open circuit is employed, or by a break in the circuit if the latter is normally closed. The watchman or other employee in charge of the section of the railway line in which the signaling instrument is disposed, or persons living near the point at which an instrument is located, are provided with keys by means of which they can operate the switch for the purpose of reversing the condition of the circuit, to render it inoperative. Inasmuch as the key is locked in the instrument after the latter has been operated by its use, it becomes necessary that the person who performed the operation notifies the signal maintainer or other authorized person, of the inoperative condition of the system. The official thus being notified has the means to restore the switch to its normal condition and at the same time remove the key, after the defect which caused the disturbance of the circuit has been corrected, and in doing so he ascertains at the same time by whom the switch was operated.

In proceeding in accordance with my invention I provide in operative connection with a switch, a mechanism which can be adjusted only by means of a key inserted through a slot in the housing in which it is inclosed. The means for the separate adjustment of the part of the mechanism which locks it in the position to which it is moved to reverse the normal condition of the switch, is accessible only at a point of the housing remote from the slot through which the key is inserted, and the entire device is inclosed in a case which has a key-hole in register with the said slot, and which is locked so that only persons in the possession of a second key are able to adjust the said locking means for the purpose of releasing the mechanism and returning it to its normal position.

An embodiment of my invention has been

illustrated in the accompanying drawings in the various views of which like parts are similarly designated, and in which,

Figure 1 represents a face view of the case 5 in which the lock switch is inclosed, Fig. 2, a transverse section through the same along the line 2--2, Fig. 1, Fig. 3, an enlarged elevation of the switch-element detached from the case, part of its front plate 10 having been broken away to reveal the interior mechanism, Fig. 4, a fragmentary view of the upper portion of the switch housing showing the operative parts in the position they occupy after they have been actuated by 15 means of the key to reverse the condition of the circuit in which the switch is connected, and, Fig. 5, a section taken along the line 5--3, Fig. 4 looking in the direction of the arrow drawn across said line.

20 Referring more particularly to the drawings, the reference character 2 designates a case provided with a door 3 which can be secured in its closed position by means of a lock the key-hole of which has been shown 25 at 4 in Fig. 1.

The case which may be used to house the batteries or other parts of the electric system to which my invention is applied, is more particularly provided to inclose the 30 switch so as to prevent access to the locking means which forms part of its mechanism, except by the use of a key which fits the lock of the door.

My improved lock switch has been shown 35 in detail in Figs. 3 to 5 of the drawings, consists of a preferably cylindrical housing 5 the detachable face plate 6 of which has two laterally projecting apertured ears 7 for the application of screws or rivets 8 by 40 means of which the instrument is mounted upon the inner surface of the door 3, as shown in Figs. 1 and 2. The face plate of the housing is attached to the body-portion of the same by means of screws 9 and it has 45 a centrally disposed key-hole 37 which registers with a corresponding hole 10 in the door 3. The switch mechanism which is assembled within the housing upon the back plate 12 of the same, comprises a circular 50 disk 13 which is mounted for rotation in the center of the housing and which has a peripheral notch 14. The member 13 is rotatably mounted upon a stud 15 which is riveted in the center of the back plate of 55 the housing and which has an extension 16 of reduced diameter to provide a pivot pin for the rotative support of an axially bored key 17 inserted through the registering key-holes of the door 3 and the plate 6. Two 60 pawls 18 and 19 which are pivotally mounted on the plate 12 at points at opposite sides of the axis of rotation of the disk 13, have at their free extremities integral detents 20 and 21 which are formed to fit in the notch

14, and they are constantly maintained in contact with the member 13 by means of springs 22 and 23 applied at their pivoted ends. The pawl 19 is furthermore provided with a pin or handle 24 which projects through a slot in the rear plate of the housing, and it engages a plate 25 of non-conductive material which is secured to the resilient blade 26 of the circuit-closing element of the instrument. The blade 26 is attached at one of its ends to the inwardly extending 70 angular shank of a binding post 27 applied exteriorly of the housing, and the opposite free extremity of the blade is adapted to engage the inwardly projecting shank of a similarly disposed, second binding post 28. 75 The two posts are secured in apertures in the rear plate of the housing, which are lined with bushings 29 of non-conductive material for the purpose of insulating the posts from each other and from the metallic 80 parts of the operating mechanism. The rotary member 13 of the latter is provided with three forwardly projecting pins, the shortest one 30 of which serves as a ward 85 which in the operation, registers with a notch in the bit 31 of a key 17 and prevents the operation of the mechanism by a key other than that especially designed for the purpose. It will be understood that the ward 30 can be positioned and formed in any suitable manner or that a plurality of wards may be provided to correspond with differently formed 90 key-bits. The two other pins 32 and 33 of the rotary member 13 are disposed to extend at opposite sides of the key-bit 17 when the latter is inserted through the registering key-holes, and they serve to limit the rotary movement of the said bit in either direction for the purpose of preventing its removal from the instrument after the operating mechanism thereof has been adjusted to 100 reverse the condition of the circuit in which the switch is connected. To determine the normal position of the rotary disk as well as that to which it is moved to reverse the 105 normal condition of the electric switch, the pin 33 is extended to project between the disk 13 and the back plate of the casing, as shown at 36 in Fig. 5, and two pins 35 are secured to the latter to provide stops which by the 110 engagement of the extension 36, arrest the 115 movements of the disk.

When the parts of the hereinbefore described mechanism are in their normal position, the detent 20 of the pawl 18 occupies 120 the notch of the rotary member 13 thereby locking the latter against rotation, and the detent 21 of the opposite pawl 19 rides upon the peripheral edge of the said member, the last mentioned pawl holding by engagement 125 with the plate 25, the blade 26 of the switch element in engagement with the shank of the binding post 28, thereby closing the circuit

of which the two posts are the terminals. To open the circuit, the key 17 is inserted through the registering key-holes in the plate 6 and the door 3 and turned about the 5 pin 16 on the stud 15 in the direction of the arrow *a* in Fig. 3. The bit 31 of the key engages a beveled face 34 on the pawl 18, which extends in its path and thereby moves the said pawl about its pivot against the action 10 of the spring 22 until the detent 20 has moved out of the notch 14. The rotary member 13 being thus free to move about its axis, is rotated by the engagement of the key-bit with the pin 32 which is sufficiently longer 15 than the pin 30 to prevent its passing through the notch in the bit 31. The member is rotated until its notch is brought in register with the detent of the opposite pawl 19 which enters the same and thereby locks 20 the member against further rotation while at the same time the blade 26 is allowed to separate from the shank of the post 28 with which it was in engagement, as shown in Fig. 4 of the drawings. The circuit is thus 25 opened and must necessarily remain in that condition until the detent of the pawl 19 is moved out of the notch of the rotary member to permit rotation of the disk to its original position, it being observed that the 30 pins 32 and 33 at opposite sides of the bit of the key, prevent the latter from being turned separately to register with the key-holes. To restore the parts to their original position after the defect in the circuit has 35 been corrected, it is necessary that the door of the case 2 be opened by means of a key which fits its lock, after which the pawl 19 is lifted by means of the pin or handle 24 which projects through the slot in the rear 40 plate of the switch housing, and the rotary member is turned by means of the key 17 until the latter is again in register with the key-holes through which it is removed from the instrument.

45 While I have shown and described my invention in the best and simplest form at present known to me, I desire it understood that changes in the construction and arrangement of its parts may be resorted to 50 within the spirit of my invention, and that while the switch illustrated in the drawings is particularly designed for use in a normally closed electric circuit, a slight variation in its construction is sufficient to adapt 55 it for the control of a normally open circuit.

Having thus described my invention what I claim and desire to secure by Letters-Patent is:

60 1. In apparatus of the character described, a circuit controlling switch, key controlled mechanism for operating the switch to open and close a circuit in which it is connected, the said mechanism including a rotary member, means for locking said member in one

of its operative positions, and means for locking the same in another one of its operative positions, and a key adapted to unlock said member by operation of the first-mentioned means and to rotate the same until it is locked by the action of the other means, the last mentioned locking means being capable of releasing the mechanism independent of any action of said key.

2. In apparatus of the character described, a circuit controlling switch, key controlled mechanism for operating the switch to open and close a circuit in which it is connected, the said mechanism including independently operable means for locking it in one of its operative positions, a removable key for the operation of said mechanism, and a housing having a key-hole for the passage of said key to place it in operative relation to the mechanism, the latter having means for preventing the return movement of the key for its withdrawal through the said key-hole, when locked in its said position.

3. In apparatus of the character described, a circuit controlling switch, key controlled mechanism for operating the switch to open and close a circuit in which it is connected, the said mechanism including a rotary member, and independently operable means for locking the latter in one of its operative positions, a key for the operation of said member, and a housing having a key-hole for the passage of said key to place it in operative relation to the said member, the said member being adapted to prevent the independent return movement of the key for its withdrawal through the said key-hole, when locked in its said position.

4. In apparatus of the character described, a circuit controlling switch, key controlled mechanism for operating the switch to open and close a circuit in which it is connected, the said mechanism including a rotary member and independently operable means for locking the latter in one of its operative positions, a key for the operation of said member, and a housing having a key-hole for the passage of said key to place it in operative relation to the said member, the said member having two pins projecting at opposite sides of the key to limit an independent rotary motion of the key in either direction.

5. In apparatus of the character described, a circuit controlling switch, key controlled mechanism for operating the switch to open and close a circuit in which it is connected, the said mechanism including means for locking it in one of its operative positions, a key for the operation of said mechanism, a housing having a key-hole for the passage of the key to place it in operative relation to the said mechanism, the latter having means for preventing the return movement of the key for its

withdrawal through the said key-hole, when locked in its said position, and the said means being adapted to be independently operated for the unlocking of the said mechanism from without the housing.

6. In apparatus of the character described, a circuit controlling switch, key-controlled mechanism for operating the switch to open and close a circuit in which it is connected, the said mechanism including a rotary member having a notch, and a pawl adapted to lock said member in one of its operative positions, by entering said notch, a key for the operation of said member, and a housing having a keyhole for the passage of said key to place it in operative relation to the said member, the latter having means to prevent the independent return movement of the key for its withdrawal through the said key-hole, when in its said position, and the said pawl having means without the housing for its independent operation to unlock said member.

7. In apparatus of the character described, a circuit controlling switch, key controlled mechanism for operating the switch to open and close a circuit in which it is connected, the said mechanism including a rotary member having a notch, a pawl adapted to lock said member in one of its operative positions by entering said notch, and a second pawl adapted to lock said member in another one of its operative positions, by entering said notch, a key for the operation of said rotary member, adapted to unlock the same by engagement with the first-mentioned pawl, and a housing having a key-hole for the passage of said key to place it in operative relation to said member, the latter having means to prevent the independent return movement of the key for its withdrawal through the said key-hole, when in its last-mentioned position, and the said second pawl having means without the housing for its independent operation to unlock said member.

8. In apparatus of the character described, a circuit controlling switch including movable and stationary contact members, key controlled mechanism for operating the switch to open and close a circuit in which it is connected, the said mechanism including a rotary member having a notch, a pawl in operative engagement with the said movable contact member, normally engaging the periphery of said rotary member and adapted to lock the same in one of its operative positions, by entering said notch, a key for the operation of said rotary member, and a housing having a key-hole for the passage of the key to place it in operative relation to said rotary member, the latter having means to prevent the independent return movement of the key for its withdrawal through the

said key-hole, when in its said position, and the said pawl having means without the housing for its independent operation to unlock said rotary member.

9. In apparatus of the character described, a circuit controlling switch, key controlled mechanism for operating the switch to open and close a circuit in which it is connected, the said mechanism including independently operable means for locking it in one of its operative positions, a key for operating said mechanism, a housing having a key-hole for the passage of said key to place it in operative relation to said mechanism, the latter having means to prevent the independent return movement of the key for its withdrawal through the said key-hole, when in its said position, and the same means being adapted to be independently operated from without the housing to unlock said mechanism.

10. In apparatus of the character described, a circuit controlling switch, key-controlled mechanism for operating the switch to open and close a circuit in which it is connected, the said mechanism including independently operable means for locking it in one of its operative positions, a key for operating said mechanism, a housing having a key-hole for the passage of said key to place it in operative relation to said mechanism which includes means to prevent the independent return movement of the key for its withdrawal through the said key-hole, when in its said position, the said means being adapted to be independently operated from without the housing to unlock said mechanism, and key-controlled means normally preventing access to the said means.

11. In apparatus of the character described, a circuit-controlling switch, key-controlled mechanism for operating the switch to open and close a circuit in which it is connected, and a key for the operation of said mechanism, the said mechanism including means for locking it in a position to which it is moved by use of the key, which means are adapted to be actuated for releasing the mechanism, independently of the key.

12. In apparatus of the character described, a circuit-controlling switch, key-controlled mechanism for operating the switch to open and close a circuit in which it is connected, and a key for the operation of said mechanism, the said mechanism being adapted to prevent the removal of the key after having been moved to a determinate position by the use thereof, and including means for locking it in its said position, which means are capable of being operated to release the mechanism independent of any action of the key.

13. In apparatus of the character de-

scribed, a circuit-controlling switch, key-controlled mechanism for operating the switch to open and close a circuit in which it is connected, a key for the operation of said mechanism, the said mechanism including means for locking it in a position to which it is moved by use of the key, which means are adapted to be actuated for releasing the mechanism, independently of the

key, and key-controlled means to prevent unauthorized access to said locking means.

In testimony whereof I have affixed my signature in presence of two witnesses.
